F. WILT

CURTAIN RETAINING DEVICE

Filed Dec. 11, 1925

FIG. I.

FIG. II.

FIG. III.

FIG. IV.

INVENTOR.

F. WILT

BY

Victor J. Evans
ATTORNEYS.

UNITED STATES PATENT OFFICE.

FRED WILT, OF SAN FRANCISCO, CALIFORNIA.

CURTAIN-RETAINING DEVICE.

Application filed December 11, 1925. Serial No. 74,853.

This invention relates to improvements in curtain retaining devices and has particular reference to a device to be employed with the ordinary curtain or drapery pole.

5 The principal object of this invention is to devise means whereby the curtain, such as employed in a doorway may be maintained fully across the door so as to act as a closure therefor, or may be retained part-way across the door so as to give access there-through.

Another object is to provide means which is simple in construction and therefore cheap to manufacture.

15 A still further object is to provide means whereby the curtain may be slid in either direction so as to open the passageway.

A still further object is to provide means whereby the retaining device will be locked 20 in open position irrespective of the manner in which the curtain is handled.

Other objects and advantages will be apparent during the course of the following description.

25 In the accompanying drawings forming a part of this specification, and in which like numerals are employed to designate like parts throughout the same,

Figure I is a fragmentary view of a door 30 having a curtain equipped with my device,

Figure II is a fragmentary detail view of one end of a curtain pole having my curtain retaining device thereon,

Figure III is an enlarged detail cross-sectional view showing the manner of locking the slider at the central point of the curtain pole, and

40 Figure IV is a view similar to Figure I, showing the curtain retaining device in a retracted position and having a portion of the curtain cut away so as to better illustrate the invention.

It is common to employ curtains or draperies in the doorway leading to booths and 45 similar enclosures and it often occurs that these curtains must be manipulated many times a day. It is particularly true in restaurants having booths where the waiter is passing in and out on many occasions.

50 Applicant has therefor devised a spring-like structure which fits loosely over the pole and is inserted in the customary runway of the curtain. This spring-like structure facilitates the slipping of the curtain upon the pole and at the same time tends to keep

the curtain stretched entirely across the door opening.

By providing simple locking mechanism at each end of the spring-like structure, applicant is enabled to re-track the spring-like 60 structure and its curtain so as to give passageway through the door and maintain the same in its re-tracked position until manually released.

In the accompanying drawings wherein 65 for the purpose of illustration is shown a preferred embodiment of my invention, the numeral 5 designates the doorway between the sides of which is placed a rod or pole 6. This pole 6 is supported in the customary 70 manner and needs no further discussion.

Mounted centrally in the pole is a latch mechanism consisting of a wire having a central portion 7 and diverging ends 8 and 9. These diverging ends 8 and 9 are connected 75 to the central portion by inclined portions 11 and 12, respectively. This construction is such that the ends 8 and 9 form cams for the lock, as will be hereinafter described.

It is understood that the ends 8 and 9 80 are secured to the rod 6 in any convenient manner. A spring 13 is introduced between the rod 6 and the central portion 7. At 14, I have shown a curtain or drape having the customary hem 16 which forms a runway through the curtain. In this runway I insert a spring-like member 17 which member is of sufficient length so that when normally expanded it will reach the entire 85 width of the door.

To each end of this spring-like member I attach a glider 18 having depending yoke 19. This yoke is provided with inclined sides 21 and 22, while at the bottom is formed an eyelet 23 to which the curtain is attached.

By viewing Figure IV, it will be seen that the distance from the pole to the bottom of the yoke is less than the internal diameter 100 of the spring-like member. This is to permit the spring-like member to pass freely over the latch mechanism above described, while the yoke when brought into contact with the latch mechanism will be retained 105 as shown in Figure IV.

The manner of operating my device is as follows:—

Assuming that the curtain has been provided with my device and is in the position shown in Figure I, the user will grasp the 110

curtain at either edge and move the curtain in such a manner as to provide a passage-way through the door. Should he move the curtain from the right, as shown in the drawings, toward the left of the door, the 5 spring-like member will be compressed as shown in Figure IV, and as soon as the yoke 19 on the right hand end of the spring engages the latch mechanism the curtain will 10 be retained in this position. Should the user be careless in the manner in which he moves the curtain to open position, the fact that the yoke 19 is provided with inclined 15 portions 21 and 22 will result in the glider 19 rotating partly around the rod and be brought back to the vertical position shown in Figure III and consequently locked.

When it is desired to close the curtain the user merely gives a pull on the edge of 20 the curtain sufficient to release the yoke from the latch mechanism and lets go. The spring in expanding will carry the curtain across the rod and entirely close the door.

It is obvious that the same procedure may 25 be employed in opening the curtain from the left hand side of the drawings.

It will also be seen that the fact that the 30 spring slides upon the rod gives practically frictionless contact in comparison to the friction contact of the usual materials, and it is much easier to manipulate the curtain.

It is to be understood that the form of my 35 invention herewith shown and described is to be taken as a preferred example of the same, and that various changes in the shape, size and arrangement of parts may be resorted to without departing from the spirit of the invention or the scope of the subjoined claims.

Having thus described my invention, I 40 claim:—

1. In combination with a curtain rod, a

spring-like member positioned thereabout, a latch mechanism centrally positioned on the 45 rod, said spring-like member being of sufficient size to pass over said latch mechanism, and a yoke secured to said spring-like member in such a manner as to engage said latch mechanism when said spring is compressed toward one end of said rod. 50

2. In a device of the character described, the combination with a curtain rod having a latch centrally positioned thereon, said latch having inclined end portions, a spring-like member surrounding said rod and said 55 latch mechanism and adapted to freely move thereover, said spring-like member being of sufficient length to normally overlie the entire length of said rod, a glider secured to each end of said spring, and a yoke secured 60 to each of said gliders and adapted to engage said latch mechanism when said spring is compressed toward one end of said rod.

3. In combination with a curtain rod, a latch mechanism centrally positioned on said 65 rod, said latch mechanism having inclined end portions, a pair of spaced gliders mounted on said rods, a yoke secured to each of said gliders and depending therefrom, said 70 yokes having inclined sides, means carried by said yoke to secure said yoke to a curtain, a spring-like member surrounding said pole, and said latch mechanism and having its ends secured to said gliders for the purpose specified. 75

4. The combination with a curtain-carrying rod, of a contractible spring member positioned on said rod, a latch member carried by said rod, and means connected to said spring member and adapted to be received in the latch member upon manual actuation of the curtain. 80

In testimony whereof I affix my signature.

FRED WILT.
